Primary Examiner—Ruth McInroy(74) *Attorney, Agent, or Firm*—Wolf, Greenfield & Sacks, P.C.(57) **CLAIM**

The ornamental design for a shaggy steam pocket, as shown and described.

DESCRIPTION

FIG. 1 is a front and left side perspective view of the shaggy steam pocket;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof;

The broken lines shown are included for illustrative purposes only form no part of the claimed design.
